UNITED STATES PATENT OFFICE.

FLEMON R. GREENE, OF BENTONVILLE, ARKANSAS.

HAY-PRESS.

SPECIFICATION forming part of Letters Patent No. 793,130, dated June 27, 1905.

Application filed November 22, 1904. Serial No. 233,853.

To all whom it may concern:

Be it known that I, FLEMON R. GREENE, a citizen of the United States, residing at Bentonville, in the county of Benton and State of 5 Arkansas, have invented a new and useful Hay-Press, of which the following is a specification.

This invention relates to hay-presses, and has for its object to produce a device of this 10 character of improved construction and increased efficiency.

With these and other objects in view, which will appear as the nature of the invention is better understood, the same consists in certain 15 novel features of construction, as hereinafter fully described and claimed.

In the accompanying drawings, forming a part of this specification, and in which corresponding parts are denoted by like designating 20 characters, is illustrated the preferred form of the embodiment of the invention capable of carrying the same into practical operation, it being understood that the invention is not necessarily limited thereto, as various changes 25 in the shape, proportions, and general assemblage of the parts may be resorted to without departing from the principle of the invention or sacrificing any of its advantages.

In the drawings thus employed, Figure 1 30 is a perspective view of a hay-press embodying the improved construction. Fig. 2 is a plan view, enlarged, of the plunger-operating portion of the device. Fig. 3 is a side elevation of the power end of the press with the 35 plunger-operating cam omitted. Fig. 4 is a transverse section on the line 4-4 of Fig. 2 looking toward the plunger-operating cam.

The improved apparatus comprises the 40 press-box 10, having the feed-hopper 11, and with the bale-box 12 extending from one side and spaced base members 13 14 extending from the other side. The base members are connected at their free ends to a transverse 45 sill member 15, suitably braced, as at 16, and provided with a buffer-spring 17, extending between the base members. Spaced guide-rails 18 19 are also attached to the inner faces of the base members and preferably formed of sections of L-bars, as shown in Fig. 4.

50 The plunger 9, operating in the press-box

10, is of the usual form and provided with the operating-beam 20, extending above the space between the base members 13 14 and provided with a depending portion 21, projecting between the base members, and provided with 55 spaced bars 22 23, between which two rollers 24 25 are journaled upon a shaft 26, the roller 24 having flanges 27 28 at the ends and extending over the upper surface of the guide-bars 18 19 and the other roller 25 operating 60 between the vertical webs of the guide members and beneath the horizontal webs of the same, as clearly shown in Fig. 4. By this means the beam 20 will be guided in its reciprocal movement and maintained in position relative 65 to the base members, the lower flange 28 of the upper roller 24 riding upon the upper faces of the horizontal webs of the guide members 18 19 and the lower roller 25 operating 70 beneath said horizontal webs of the guide-bars and between the vertical webs thereof, so that the beam will move with the minimum of friction and will be prevented from either lateral or vertical displacement.

Attached to the sill member 15 is a standard 75 29, upon which an S-shaped cam member 30 is pivoted, and to this cam member the "sweep" 32 is attached. The S-cam member alternately engages the roller 24 as the sweep is rotated by the horse or horses connected to its free end, and thus produces the 80 requisite reciprocal movement to the plunger in the press-box.

The beam 20 is provided with a retracting-spring 35 for returning the beam and plunger 85 after release by the rotating cam, and the impact of the rapid return stroke is received by the buffer-spring 17 and absorbed thereby and prevented from being imparted to the framework or other parts.

The device is simple in construction, inexpensive to manufacture, strong and durable, and will operate efficiently and with the minimum of friction and power.

Generally one horse will be sufficient to operate the apparatus; but any number may be employed.

Having thus fully described the invention, what is claimed is—

1. In a hay-press, a press-box having pro- 100

- jecting spaced base members, a plunger for reciprocation in said press-box, a plunger-beam having a portion depending between said base members and guided thereby, a roller 5 mounted for rotation upon said beam and having lateral flanges extending above said base members and riding thereon, and a cam member mounted for rotation upon said base member and operative against said roller between 10 its flanges.
2. In a hay-press, the combination with a plunger-beam, of parallel beams provided with inwardly-extending guide-webs, and rollers carried by the plunger-beam respectively 15 above and below said guiding-webs for contact with the corresponding faces thereof, and means for operating the plunger.
3. In a hay-press, the combination with a plunger-beam, of parallel guiding-beams having inwardly-extending webs, upper and lower 20 rollers carried by the plunger-beam respectively above and below the plane of said webs, and plunger-operating means having a cam for operation in contact with one of said 25 rollers.
4. In a hay-press, the combination with a plunger-beam, of parallel guiding-beams having inwardly-extending webs, upper and lower rollers carried by the plunger-beam respectively 30 above and below the plane of said webs, the lower roller operating between said webs and approximately fitting in the interval therebetween, and plunger-operating means having a cam for operation in contact 35 with the upper roller.
5. In a hay-press, a press-box having spaced base members extending therefrom, a plunger, a plunger-beam having a portion depending between said base members and guided there- 40 by, straps connected to the free end of said beam and supporting a shaft between the straps, a roller mounted for rotation upon said shaft and extending over said base members, a roller mounted for rotation upon said shaft and operating between said base members, and a cam member mounted for rotation upon said base members and operatively engaging one of said rollers. 45
6. In a hay-press, a press-box having spaced base members provided with L-shaped guide-bars, a plunger, a plunger-beam having a portion extending between said base members, a roller mounted for rotation upon said beam and extending over the base members, a roller mounted for rotation upon said beam and extending between said base members and beneath the horizontal webs of said guide-bars and a cam member mounted to operate against said first-named roller. 50
7. In a hay-press, a press-box having spaced base members provided with L-shaped guide-bars, a plunger, a plunger-beam having a portion extending between said base members, a roller mounted for rotation upon said beam and extending over the base members, a re- 55 tracting-spring connected to maintain said beam yieldably in withdrawn position, a cam member to operate against said roller, and a buffer-spring for receiving the impact of said beam when released by said cam. 60
- 7c
- In testimony that I claim the foregoing as my own I have hereto affixed my signature in the presence of two witnesses.

FLEMON R. GREENE.
